UNITED STATES PATENT OFFICE

147,553

DESIGN FOR A HANDLE MEMBER FOR
KNIVES AND FORKS AND SIMILAR
ARTICLES

James L. Hvale, Chicago, Ill., assignor to Eko Products Company, Chicago, Ill., a corporation of Illinois

Application April 24, 1946, Serial No. 128,923

Term of patent 14 years

(Cl. D44—29)

To all whom it may concern:

Be it known that I, James L. Hvale, a citizen of the United States, residing at Chicago, in the county of Cook and State of Illinois, have invented a new, original, and ornamental Design for a Handle Member for Knives and Forks and Similar Articles, of which the following is a specification, reference being had to the accompanying drawing, forming part thereof.

Fig. 1 is a side elevational view of the handle member for knives and forks and similar articles, showing my new design.

Fig. 2 is a similar view illustrating the appearance of the handle member when turned through an angle of 90 degrees about its longitudinal axis relative to the position thereof as shown in Fig. 1.

I claim:

The ornamental design for a handle member for knives and forks and similar articles, as shown.

JAMES L. HVALE.
